ADJUSTABLE RECLINING CHAIR

James C. Witty, Troy, Ohio, assignor to The Troy Sun-shade Company, Troy, Ohio, a corporation of Ohio

Application October 15, 1954, Serial No. 32,686

Term of patent 7 years

(Cl. D15—11)

FIG-3

Fig. 1 is a perspective view of an adjustable reclining chair embodying my new design illustrating the seat element in an upright position;

Fig. 2 is a perspective view of the chair as seen from the rear of Fig. 1; and

Fig. 3 is a side perspective view of the chair with the seat element adjusted to a fully reclined position.

I claim:

The ornamental design for an adjustable reclining chair, substantially as shown.
